MOLDING MACHINE

Frank R. Wallace, Philadelphia, Pa., assignor to
The Tabor Manufacturing Company, Philadelphia, Pa., a corporation of Pennsylvania

Application May 14, 1937, Serial No. 142,544

6 Claims. (Cl. 22—45)

The present invention relates to improvements in molding machines and more particularly to valveless jarring, squeezing molding machines.

One object of the present invention is to relieve 5 the mechanism which actuates the jarring table from shock by the jarring table and from the weight carried by the jarring table.

Another object of the invention is to guard 10 against the accidental escape of the squeezing 10 piston from its cylinder.

Another object of the invention is to lighten the construction of the squeezing cylinder.

Another object of the invention is to provide 15 a molding machine of the type mentioned which shall be strong, efficient and yet comparatively inexpensive.

Other objects of the invention will appear from the following description at the end of which the invention will be claimed.

Generally stated, the invention consists in a 20 fixed base having upstanding ribs at its top, a jarring table having bottom ribs arranged to cooperate with the upstanding ribs and a pneumatic cylinder structure suspended from the base 25 with clearance between it and the jarring table in all positions thereof and adapted to operate the jarring table.

The invention also comprises the improvements 30 to be presently described and finally claimed.

In the following description reference will be 35 made to the accompanying single figure of the drawing which is a central sectional view of so much of a molding machine as is necessary for an understanding of the invention and which 40 also diagrammatically illustrates a ramming block.

In the drawing, 1 indicates a hollow base having 45 an inturned annular flange 2 at its top. The base 1 may be appropriately mounted on wheels, 50 although the latter are not shown because they are too well understood to require illustration or description. 3 is a hollow jarring base having at its bottom an inturned annular flange 4 mounted on and extending inward beyond the 55 flange 2. The jarring base 3 at its top is equipped with upstanding concentric ribs 5 and 6 and with a guide sleeve 7 depending from the inner rib 6. 8 is a squeezing cylinder depending from the flange 4 of the jarring base into the hollow base. Inasmuch as it does not receive the shock or weight of the jarring table it may be made of 60 comparatively thin sheet metal. 9 is a squeezing piston arranged in the squeezing cylinder 8 and it is of greater diameter than the opening 55 in the flange 4. In this way the piston 9 may not

accidentally escape from the cylinder 8. 10 is a piston rod connected with the piston 9 and it is arranged in the guide sleeve 7 and it provides a plunger barrel 11 open at its top. 12 is a jarring table spaced from the plunger barrel as at 13 and provided with a plunger 14^a arranged in the plunger barrel. The jarring table is provided with an annular rib 14 and an annular head 15. The rib 14 is aligned with the rib 5 and the head 15 is aligned with the rib 6. 16 is a fluid pressure connection for the cylinder 8 and the piston 9 is shown to normally rest upon its end. It also operates as an exhaust connection. 17 is a groove on the plunger barrel 11 and 18 is a groove on the plunger 14^a. These 15 grooves 17 and 18 intercommunicate when the plunger is retracted as shown in the drawing. 19 is a port from the groove on the plunger through the wall of the plunger to the interior of the barrel 11 below the end of the plunger. 20 20 is a pressure connection through the guide sleeve to the groove 17 on the plunger barrel. 21 is an exhaust port through the barrel and it is arranged to be uncovered by the plunger at the end of its outward stroke. 22 is a guide pin 25 connection between the base and the jarring table. 23 is an inlet for oil. 24 diagrammatically indicates a ramming block or head.

The mode of operation may be described as follows: To jar, fluid under pressure is introduced at 20 into the space in the plunger barrel beneath the plunger 14^a so that the latter rises carrying with it the jarring table 12, and when it rises far enough to uncover the exhaust port 21 the plunger and table fall and the ribs 5 and 35 14 and 6 and 15 receive the shock which is transmitted to the base. This operation is repeated until sufficient jarring has been accomplished. To squeeze fluid under pressure is introduced through the connection 16 so that the piston 9, 40 its rod and all the parts carried thereby including the jarring table are raised toward the ramming head and thereafter the parts are lowered by exhausting through the connection 16. The spring 25 ensures the downward movement of 45 the parts.

It will be obvious to those skilled in the art to which the invention relates that modifications may be made in details of procedure without departing from the spirit of the invention which is 50 not limited to such matters or otherwise than the prior art and the appended claims may require.

I claim:

1. A molding machine of the valveless jarring 55

- squeezing type comprising in combination a hollow base having an inturned annular flange at its top, a hollow jarring base having at its bottom an inturned annular flange mounted on and extending inward beyond the first mentioned flange and having at its top upstanding concentric ribs and a guide sleeve depending from the inner rib, a squeezing cylinder depending from the flange of the jarring base into the hollow base, a spring 10 pressed piston in the squeezing cylinder of greater diameter than the opening in the annular flange at the bottom of the jarring base, a piston rod connected with the squeezing piston and arranged in the guide sleeve and providing a 15 plunger barrel open at its top, a jarring table spaced from the plunger barrel and provided with a plunger arranged in the barrel and with projections adapted to cooperate with said ribs, and fluid connections for actuating the piston and plunger.
2. In a jarring-squeezing molding machine a jarring table, a plunger and plunger barrel for operating the same, grooves on the plunger and on the plunger barrel adapted to intercommunicate when the plunger is in retracted position, a 25 port from the groove on the plunger through the same to the interior of the barrel, a guide sleeve in which the barrel is arranged, a pressure connection through the guide sleeve to the groove on the barrel, and an exhaust port through the barrel arranged to be uncovered by the plunger at the end of its outstroke.
3. In a jarring and squeezing molding machine, the combination of, a jarring table, a jarring plunger connected with said jarring table, a squeezing piston, a piston rod connected with said squeezing piston and having a bore at its upper end providing a barrel in which the jarring plunger is arranged for operation, and a spring 35 stressing said piston rod out of contact with said jarring table.
4. In a jarring and squeezing molding machine,

the combination of, a jarring table, a jarring plunger connected with said jarring table, a cylinder co-operating with said plunger and defining a space therebetween, an inlet for operating fluid passing through said cylinder, a port in 5 said jarring plunger located so as to conduct fluid from said inlet to said space in one position of said plunger, said plunger being adapted to cut off said inlet upon movement from said position, an outlet for fluid from said space, and 10 means for controlling the flow of fluid through said outlet.

5. In a molding machine of the jarring and squeezing type, a hollow base of substantial construction adapted to receive the shock of the 15 jarring operation, a squeezing cylinder structure mounted on said base, a squeezing piston structure co-operating with said squeezing cylinder structure and having its top located beneath the 20 top of said base when said squeezing piston structure is in retracted position, and a jarring table mounted on said base above said squeezing piston structure so as to be engaged and moved by said squeezing piston structure during the squeezing operation and arranged to contact with the 25 top of said base and to avoid contact with said squeezing piston structure during the jarring operation so that the shock of said jarring table is transmitted directly to said base.

6. The combination in a jarring-squeezing 30 molding machine of a fixed base having upstanding ribs at its top, a jarring table having on its bottom ribs arranged to contact with said upstanding ribs, a pneumatic squeezing cylinder structure suspended from said base, and a squeezing 35 piston structure mounted in said squeezing cylinder structure and arranged to operate said jarring table during the squeezing operation and to have its top located beneath the top of said base and out of contact with said jarring table 40 during the jarring operation.

FRANK R. WALLACE.
